UNITED STATES PATENT OFFICE.

WILLIAM H. LORD, OF NEW YORK, N. Y.

SPEED-CLOCK FOR MACHINERY.

SPECIFICATION forming part of Letters Patent No. 298,487, dated May 13, 1884.

Application filed October 4, 1883. (No model.)

To all whom it may concern:

Be it known that I, WILLIAM H. LORD, of the city, county, and State of New York, have invented a new and useful Improvement in 5 Speed-Clocks for Machinery, of which the following is a full, clear, and exact description.

Reference is to be had to the accompanying drawings, forming a part of this specification, in which similar letters of reference indicate 10 corresponding parts in all the figures.

Figure 1 is a front elevation of my improvement, the driving-shaft being shown in section. Fig. 2 is a sectional plan view of the same.

15 The object of this invention is to provide a means for showing the loss or gain in speed of a steam-engine or other machinery.

The invention consists in a speed-clock for machinery, constructed with an ordinary clock-work provided with a third hand connected by a shaft and gearing with the machinery, and a clock-work provided with two hands arranged to revolve, the one once an hour and the other once in sixty hours, as will be 25 hereinafter fully described.

A is the driving-shaft whose speed is to be registered, and to which is attached a worm, B. The worm B meshes into the worm-wheel C, attached to the end of a short shaft, D, 30 which revolves in bearings in some suitable support, and upon the other end of which is placed a small gear-wheel, E. The gear-wheel E is connected with the shaft D by a tongue and groove, so that it can be moved longitudinally upon the shaft D while being carried around by and with the said shaft in its revolution.

In the projecting end of the hub of the gear-wheel E is formed an annular groove to 40 receive the forked end of the lever F, which is pivoted to some suitable support, so that the movement of the said lever F will move the gear-wheel E into and out of gear. The teeth of the gear-wheel E mesh into the teeth 45 of the larger gear-wheel G, attached to the end of a shaft, H, which revolves in suitable supports, and passes through the clock-works I and J. The clock-work I is made the same as the work of an ordinary clock, except that 50 the post K of the hour-hand L and the post M of the minute-hand N are both tubular, and through them passes a post, O, carrying a third hand, P.

To the post O is attached a worm-wheel, Q, which meshes into a worm, R, attached to the 55 shaft H, the gearing of which is so arranged that the minute-hand N and the speed-hand P will keep together when the shaft A is driven at the proper speed; but should the shaft A run too slow or too fast the speed-hand P will be in advance of or behind the said minute-hand, and will thus show the variations of speed. The clock-work I is driven by a spring or weight in the ordinary manner.

To the shaft H is attached a worm, S, which 65 meshes into the worm-wheel T, attached to the post U, which carries the minute-hand V, the shaft H being so geared that the hand V will make a revolution in one hour. The tubular post W, that carries the hour-hand X, 70 is connected with the post U by gearing so constructed that the said hour-hand X will make a revolution in sixty hours, that being the number of hours that machinery usually runs in a week.

75 With this construction the clock I shows whether the machinery is running too fast or too slow or at the required speed, and the clock J shows how much speed, if any, has been lost during so much of the week as had 80 passed when the observation was taken.

Having thus described my invention, I claim as new and desire to secure by Letters Patent—

1. A speed-clock for machinery, constructed substantially as herein shown and described, 85 and consisting of an ordinary clock-work provided with a third hand and connected by a shaft and gearing with the machinery, and a clock-work connected with the machinery by a shaft and gearing, and provided with 90 two hands arranged to revolve, the one once an hour and the other once in sixty hours, as set forth.

2. In a speed-clock for machinery, the combination, with the drive-shaft A, of the clock-work J, provided with two hands, V X, geared to revolve, the one once an hour and the other once in sixty hours, the shaft H, and the connecting-gearing, substantially as herein shown and described, whereby the amount 100 of lost speed will be indicated, as set forth.

WILLIAM H. LORD.
